UNITED STATES PATENT OFFICE.

JAMES J. BRAWNER AND GEORGE HOWARD, OF LINDALE, TEXAS.

COUNTER DISPLAY AND DISPENSING CASE.

Application filed October 14, 1924. Serial No. 743,558.

The object of the invention is to provide a simple and inexpensive display and dispensing case adapted for placement on a counter for the ready dispensing, through sale, of staple commodities; to construct the case of compartmental form with a compartment for each commodity and a related display compartment with each compartment for the display of samples; and to provide for the ready access to the main or dispensing compartments and the sample compartments.

With these objects in view, the invention consists in a construction and combination of parts of which a preferred embodiment is illustrated in the accompanying drawings, wherein:

Figure 1 is a plan view of the invention.

Figure 2 is a vertical transverse sectional view on the line 2—2 of Figure 1.

Figure 3 is a horizontal longitudinal sectional view on the line 3—3 of Figure 2.

The case is preferably of a shallow depth and the bottom 1 is preferably dimensioned to the counter on which the case is placed and may be of any extent desired to provide the necessary number of compartments. The front and rear walls 2 and 3 are spanned by division walls 4 to define dispensing compartments 5 arranged in pairs and accessible through hingedly mounted doors 6.

The front face of the case is arranged at an angle as indicated and opposite each compartment 5 is a display compartment 7 for the display of samples, each display compartment having a rear wall inclined to direct the contents toward the transparent panel 8 which is preferably of glass. The transparent panel 8 of each display compartment is removable, being mounted in grooves 9 formed in the sides of blocks 10 constituting the division members between the display compartments and the spacing members between the front and rear walls thereof to give said compartments width.

A common closure is provided for the display compartments and consists of a strip 11 hingedly mounted on a fixed strip 12 extending longitudinally of the case. The closure 11 is held in its closed position by a latch member 14 which may be of any conventional form.

When it is desired to change the samples in the display compartments, the closure member 11 is unlatched and raised and the transparent panel of any compartment may then be lifted and the contents will flow out at the bottom edge and either a new sample or a sample of a different commodity placed therein, the commodity corresponding to the sample being placed in the compartment 5 just back of the display compartment.

In order to provide for the ready opening of the doors or covers 6, they are extended beyond the rear wall 3 to provide overhanging edges 15 which may be readily gripped to raise or open the doors or covers. Thus, no knobs or the equivalent are required to open the doors or covers and the top of the case is practically unobstructed except for the small space occupied by the hinges.

The invention having been described, what is claimed as new and useful is:

A case for the purpose indicated having dispensing and display compartments of which the latter is disposed directly in front of the former and arranged at an inclination from a vertical plane, individual swinging closures for said compartments, a transparent panel constituting the front wall of the display compartment, and guides, in which the panel is slidably supported for its ready removal, the closure for the display compartment engaging the upper edge of said panel.

In testimony whereof they affix their signatures.

GEORGE HOWARD.
JAMES J. BRAWNER.
